(57) **CLAIM**

We claim the ornamental design for a full or near-full cut-off visor for light fixture, substantially as shown.

DESCRIPTION

FIG. 1 is a perspective view of an exemplary embodiment of the present invention.

FIG. 2 is a top plan view of FIG. 1.

FIG. 3 is a bottom plan view of the fixture of FIG. 1.

FIG. 4 is a right side view of the fixture of FIG. 1.

FIG. 5 is a left side view of the fixture of FIG. 1.

FIG. 6 is a front elevation view of FIG. 1; and,

FIG. 7 is a back elevation view of the fixture of FIG. 1.

The structure in ghost lines in FIGS. 1, 2, 3, 4, and 5 shows intended environment and does not form a part of the claimed invention.
